UNITED STATES PATENT OFFICE.

VINCENT DE LALLA, OF JERSEY CITY, NEW JERSEY.

INTERNAL-COMBUSTION ENGINE.

1,204,958.

Specification of Letters Patent. Patented Nov. 14, 1916.

Application filed May 15, 1915. Serial No. 28,380.

To all whom it may concern:

Be it known that I, VINCENT DE LALLA, a subject of the King of Italy, residing at Jersey City, in the county of Hudson and State of New Jersey, have invented certain new and useful Improvements in Internal-Combustion Engines, of which the following is a specification.

It is a purpose of this invention to effect important improvements in the construction of internal combustion engines of the reciprocating type operating on the principle illustrated in the Gile patent numbered 735,964, which are necessary in order that such an engine may be made practical.

It is essential in engines of this type that a gas-tight sliding fit be made between the flying piston and the piston rod, and as it is impossible under present methods to provide a packing element on the flying piston it is a valuable attainment of my invention that a satisfactory means for this end is provided.

It is another important aim of the invention to eliminate concussion in the engagement of the flying piston and the piston head, or by engagement of the flying piston or connected parts with other elements whatsoever.

Another purpose is to provide a compressor device having a peculiar operative relation to the piston head and flying piston, and so associated therewith as to serve as a cushion means for the flying piston.

Additional objects, advantages and features of invention will appear from the construction, arrangement and combination of parts in one embodiment of my invention as hereinafter set forth and shown in the drawings, where—

Figure 1 is a longitudinal sectional view of an engine, Fig. 2 is a detail of a pump device associated with the piston rod, omitted from Fig. 1, Fig. 3 is a formal showing of the engine in section at the beginning of a working stroke at one end, Fig. 4 is a similar view at the conclusion of the same working stroke, Fig. 5 illustrates the functioning of the piston head between the completion of the working stroke mentioned and the beginning of a scavenging stroke at the same end of the cylinder, Fig. 6 illustrates the relation of the parts at the beginning of said scavenging stroke.

There is illustrated an engine comprising twin cylinders 10 and 10' in coaxial opposed

relation, preferably cast in one piece, although methods for forming the cylinders will readily suggest themselves to those versed in the art. The cylinders are closed by identical heads 11, the cylinders and heads being water jacketed in a suitable manner. The cylinders are slightly enlarged at their outer parts, as at 12, to form a by-pass recess for a purpose to be explained. The engine includes a crank shaft 13 of ordinary form, upon which there is fixed the flywheel 14 and timing gear 15, from which connections are extended to a valve cam 16 synchronized with the shaft. Push rods 17 of usual form are mounted on the sides of the cylinders having wipers to engage the cam for alternate reciprocation of the rods, the latter being connected to the customary rocking arms 18 on respective cylinder heads, constructed and arranged to bear upon the spring-pressed stems of valves 19 seated in exhaust ports 20 formed in the heads from which suitable cored passages extend to the exterior in the most convenient direction. It is to be noted that the cam 16 is so formed and arranged as to open the valves when the crank 21 of the shaft 13 is approaching respective opposite dead centers, and will maintain the valves in open position during movement of the crank through an arc of something more than 180 degrees, as will appear.

The cylinder heads are concentrically bored, the one next the crank shaft having a larger bore than the other, and suitable packing boxes 22 23 are provided outwardly of these bores. A hollow piston rod 24 is engaged through the large bore, while an ordinary piston rod 25 is engaged through the other, these being connected to respective ends of a flying piston 26 snugly fitted and reciprocable in the cylinders. The flying piston comprises two circular plates 27—27' connected and held in rigid spaced relation by suitable tie bolts 28. These are so spaced that when the flying piston is at one limit of its movement, the opposite plate is spaced inwardly of the meeting plane of the cylinders. A piston head 30 is fitted to the cylinders and disposed between the plates of the flying piston, its axial dimension being less than the space between the plates; this head being suitably apertured for passage of the bolts 28 therethrough. The plate 27 has the rod 24 connected thereto and is concentrically aper-

tured for the passage of a main piston rod 25^a, engaged snugly in the hollow rod 24 and connected to the piston head 30. The rod 25 is connected to the plate 27' and 5 stops short therein, as does the rod 24 in the plate 27.

The cylinder casting is formed with an annular inlet passage 29 therearound at its middle, and without the walls of the 10 cylinder proper, a multiplicity of ports 31 opening therefrom through the inner wall of the casting. A pipe connection 32 for this passage is formed at one side of the casting from which a gas pipe 33 extends 15 to a compressor 34 comprising a pump cylinder 35 coaxial with the engine cylinders and spaced a short distance from the outer one, in which a piston 36 is fitted, operated by the stem 25. This compressor may be of 20 any customary double acting pump construction, and is illustrated in a formal manner, the details of valves therefor being sufficiently well understood to require no 25 illustration.

At the intake side suitable connections 30 are made with a carburetor 37. The size and position of the cylinder 35 is such that maximum compression will occur therein at each end as the flying piston reaches 35 respective limits of its movement.

The main piston rod 25^a is connected to the connecting rod 38 in a suitable manner, and this connection includes a yoke 39 fixed on the end of the rod and having two laterally 40 opening passages 40 and 41 therein, communicating with corresponding passages 40' 41' in the rod 25^a and opening laterally therefrom within the piston head, into which the rod is extended, as shown. 45 A duct arm 42 is mounted on one side of the yoke 39 in communication with the passage 40, this arm being connected to the hollow stem 43 of a piston 44 in an air pump 45 the cylinder of which is mounted parallel 50 to the axis of the rod 25^a. The piston 44 is hollow, and provided with inlet ports 46 in opposite faces, in which check valves 47 seat. Suitable valved inlets 48 are provided at each end of the cylinder of the pump, 55 whereby as the engine operates a cooling fluid may be forced to circulate in the piston head. Either air or water may be used as the cooling medium, air being contemplated in the present instance which is permitted to discharge from the passage 41 of the piston rod yoke, after leaving the piston head through the main stem.

Any suitable ignition device may be used, 60 spark plugs 50 being illustrated the circuits and timing of which are well understood and are not illustrated, therefore.

The connections between the timing gear 15 and the cam 16 include simply a counter shaft 51, having beveled gears 52 at respective ends, one meshed with the gear 15,

while the other meshes with a gear 53 mounted on the shaft 54 of the cam, which is carried by a bracket 55 on the cylinder casting.

The parts being in the positions illustrated in Fig. 3 and an explosive charge being ignited in the upper end of the cylinder while the crank is moving to the right, the charge will act against the plate 27', which is at this time in snug engagement with the opposed face of the piston head. This will move the piston head downwardly under expansion of the charge, transmitting motion to the crank shaft through the main piston rod 25^a and the connecting rod 38. 70 Maintaining the same relative positions the piston parts are thus carried to the lower part of the lower cylinder operating on the principle suggested in Fig. 4. At the same time the piston 36 of the compressor has 80 been moved compressing a charge into the pipe 33 and inlet passage or chamber 29, wherein it is maintained for a time. The ports 31 are for the moment closed by the side of the piston head. The momentum 90 imparted to the parts then carries the piston head farther downward, independently of the flying piston, which will then be checked by the high compression of the charge upon which the piston 36 is acting, 95 or, it may even be partly checked by such compression before and its movement slightly retarded so that relative movement of the piston head might occur before the parts reach the position shown in Fig. 4. 100 The effect is that the flying piston is stopped without a knock and there is no abrupt engagement between the piston head and the flying piston, comparatively speaking, such as to cause disagreeable knocking. In this 105 relative movement of the piston head toward the plate 27', the previously compressed charge is admitted between the piston head and the plate 27'. A charge is now exploded at the lower end of the lower 110 cylinder, which acts upon the piston parts to reverse their movement in the same manner that they were first moved downward, the charge admitted between the piston head and the plate 27' being thus carried 115 upwardly until the flying piston is checked in its upward movement by the cushioning effect of the compressor 34, as described, when the relative movement of the piston head and its expansive action causes the charge to pass into the lateral enlargement of the upper cylinder and past the plate 27' into the explosion chamber or space between the flying piston and the head of the cylinder. When this movement of the charge is completed it is ignited and the flying piston and piston head are in position to move with each other under the effect of the expanding charge.

The efficiency of a four cylinder four 120

cycle engine of the ordinary type is thus attained by the use of a single cylinder casting and one piston, operating as a tandem cylinder engine.

5 It will be seen that the structural details of the engine are comparatively simple for the attainment of the ends in view, although I do not regard the invention as limited to the specific construction shown.

10 While a packing 60 is shown on the outer end of the rod 24 around the rod 25, a snug fit of the two rods with each other will make the packing unnecessary, when properly lubricated.

15 What is claimed:

1. In an engine of the class described, a cylinder having a head, being laterally enlarged adjacent said head and having an inlet port at its inner part, a floating piston 20 in the cylinder having a space therein opening on its periphery for communication with the space in said enlargement when the floating piston is at the outer limit of its movement, a piston head reciprocable in 25 the floating piston, driven connections therewith, a reciprocating pump having a stroke

proportioned to that of the floating piston, operative connections between the pump and floating piston, and duct connections between pump and said inlet passage.

2. In an engine of the class described, a cylinder having a head, a piston, a floating piston interposed between the head and piston and having lost motion connection with the piston, a reciprocating piston pump 30 having the same axial direction as said cylinder, and having a stroke length corresponding to that of the floating piston, rigid connections between the floating piston and pump piston, and duct connections 35 between the pump and cylinder opening into the latter at a point intermediately of the pistons when spaced apart and at the limit of their movement away from the head.

40 In testimony whereof I have affixed my signature in presence of two witnesses.

VINCENT DE LALLA.
